UNITED STATES PATENT OFFICE

127,737

DESIGN FOR A PERFUME CONTAINER OR THE LIKE

Charles H. Foster, New York, N. Y., assignor to Babs Creations, Inc., New York, N. Y., a corporation of New York

Application March 20, 1941, Serial No. 99,743

Term of patent 7 years

To all whom it may concern:

Be it known that I, Charles H. Foster, a citizen of the United States and a resident of the city of New York (Borough of Manhattan), in the county and State of New York, have invented a new, original, and ornamental Design for a Perfume Container or the like, of which the following is a specification, reference being had to the accompanying drawing, forming part thereof, in which—

Fig. 1 is a front elevational view of a perfume container or the like showing my new design;

Fig. 2 is a rear elevational view of the container;

Fig. 3 is a top plan view;

Fig. 4 is a side elevational view.

The opposite side of the container is similar in appearance to the side shown in Fig. 4.

I claim:

The ornamental design for a perfume container or the like, substantially as shown and described.

CHARLES H. FOSTER.
